GARMENT SPOTTING MACHINE

William C. Glover, Jr., Kansas City, Mo., assignor
to Bill Glover Incorporated, a corporation of
Missouri

Application March 18, 1950, Serial No. 150,504

12 Claims. (Cl. 68—5)

1

The present invention relates in general to the removal of spots from fabrics and it deals more particularly with the construction of an improved spotting machine to be used for this purpose.

It is the object of the invention broadly speaking to provide a machine which places at the disposal of its operator means for dealing with practically every kind of spot or stain encountered in laundry and dry cleaning practice, a machine which makes possible the removal of all such spots in the most expeditious and satisfactory manner.

Another object of the invention is to provide at least one work surface which is foraminous and has means for drawing a suction therethrough, which suction means is automatically rendered effective when the surface is put into use and rendered inactive when the use is discontinued. A collateral object is to provide a work surface which is adjustable in position to suit the convenience of the operator and also is shiftable into and out of working position.

Another object of my invention is to provide a spotting machine having facilities for treating a fabric disposed on any work surface with dry steam, wet steam, cold water or hot air at will. More particularly it is an object to provide a gun operable at will to discharge a spray of cold water, and a second gun selectively operable to discharge dry steam, wet steam or hot air. In the case of all of these fluids it is an aim of the invention to make the rate or pressure of discharge readily controllable.

Still another object is to provide a spotting machine having means for generating from steam its own cold water for the treatment of thermo-setting water soluble spots, thereby eliminating the need for a separate, external water supply line.

Yet another object is to provide a machine of the character indicated having means facilitating the cleaning of various parts which in the course of normal use collect lint, sediment and other foreign matter.

Other and further objects, together with the features of novelty whereby the objects are achieved, will appear in the course of the following description of the invention.

In the accompanying drawings which form a part of the specification and are to be read in conjunction therewith, and in which like reference numerals are employed to indicate like parts of the various views

Fig. 1 is a front perspective view of my improved garment spotting machine.

2

Fig. 2 is a plan view of the machine,

Fig. 3 is an enlarged cross sectional view taken along the line 3—3 of Fig. 2 in the direction of the arrows,

5 Fig. 4 is an enlarged vertical cross section taken along the plane 4—4 of Fig. 1 in the direction of the arrows,

Fig. 5 is a horizontal cross section taken along the line 5—5 of Fig. 4,

10 Fig. 6 is an enlarged fragmentary cross section taken along the line 6—6 of Fig. 2 in the direction of the arrows,

Fig. 7 is a vertical cross section taken along the line 7—7 of Fig. 2,

15 Fig. 8 is an enlarged sectional elevation taken along the line 8—8 of Fig. 1 in the direction of the arrows, and

Fig. 9 is a schematic diagram of the air-water-steam and vacuum system employed in my machine.

20 In general, my machine comprises a base 10 having uprights which carry a chemical tray 11, a small spotting table 12, a larger spotting table 13 and a basket 14. As may be appreciated from

25 Figs. 1 and 2, the larger spotting table (which hereinafter will sometimes be referred to as the main table) is spaced above the basket with its center line normally slightly forward of the center line of the basket, that is to say, slightly nearer the operator; the smaller spotting table (which will sometimes be referred to as the auxiliary table) is positioned above and rearwardly of the main table, while the chemical tray is above and behind the auxiliary table in "stair step" relationship.

30 Considering the construction more in detail, the base 10 is T-shaped having a tubular stem 10a extending longitudinally of the machine and joined at one end to the mid portion of a narrow crosswise housing 10b. Holes 10c provided at the extremities of these members make it possible to bolt or otherwise secure the base to the floor.

35 A hollow pedestal 16 extends vertically from the base and has telescoped into its upper end a post 17 which carries the main spotting table 13. The upper portion of the hollow pedestal is slit longitudinally to form a clamping collar and is provided with outturned ears 18 on either side of the slit; by means of a dog-leg lever 19 screw

40 threadedly connected at one end to the ears, they may be drawn together to clamp the post or may be loosened to release same. Thus the main spotting table may be raised or lowered to the elevation most convenient for the operator and 45 may be locked in adjusted position by lever 19.

The main table has a horizontal heel section 21 preferably formed of an imperforate slab of hard material which is highly resistant to the corrosive action of the chemicals used in the spotting operation. At the end of this is a tapered upwardly pitched nose section comprising a pan 22 with a foraminous cover 23 of stainless steel or the like.

As best seen in Fig. 7, the cover is held in place on the pan by a pair of crossed straps 24 located on its underside; these straps, each bent to form a shallow V, are secured at their ends to the margin of the foraminous cover, and at their intersection, have a welded on nut 25 adapted to receive a threaded stem extending through the bottom of the pan from knob 26. By turning this knob to unscrew the threaded connection, the cover may be easily removed when desired to clean the pan of the lint, etc., carried thereinto in the normal use of the machine. The lowermost end of the pan is provided with a drain outlet 28 communicating with the pipe 29 which runs under the heel section of the table and connects to a flexible hose 30 leading to any suitable point of discharge.

Basket 14 comprises a generally oval panel 32 of canvas, or other suitable fabric, suspended rather loosely in hammock fashion from an open frame loop 33 whose ends are secured to a split collar 34 encircling post 17. The collar is slideable up and down the post to adjust the elevation of the basket relative the main spotting table, and by means of lever 35, one end of which is screw threadedly connected to lugs on the split collar, the latter may be clamped tightly to the post to hold the basket in any selected position.

It is the function of the basket to receive depending portions of a garment being treated, thus to keep same off the floor and out of the way of the operator. As previously noted, the center line of the basket preferably is located rearwardly of the center line of the main spotting table (see Fig. 2) and it will be observed from Fig. 1 that the rear edge of the basket is somewhat higher than the forward edge, it having been found that this arrangement is best suited to catching garments during the manipulation thereof; at the same time it leaves a wide opening below the main table on the "operator side" of the machine to permit the operator easily to reach any depending portion of a garment in order to shift same to the top of the table.

The chemical tray 11 and the auxiliary spotting table 12 are supported on an upright tubular housing 38 that also functions as a steam separator as will be explained presently. This housing is spaced rearwardly of the pedestal 16 and is connected thereto by a cross brace 39. As best seen in Figs. 4 and 5, a lug 40 extends forwardly from housing 38 and carries a bearing sleeve 41. In the latter sleeve is a freely rotatable post 42 carrying at its upper end a horizontal pipe 43 which in turn supports the auxiliary table 12. A lever arm 45 is attached to post 42 by means of a collar 46 having thumb screws 47, the collar resting upon the upper end of the sleeve and forming an end bearing to support the post. By loosening the thumb screws, post 42 can be adjusted up or down relative the collar in order to adjust the elevation of the auxiliary spotting table.

The forward end of pipe 43 opens into a shallow, sloping pan 49 which is covered by a fo-

raminous oval plate or screen 50; the opposite end of the pipe connects to a flexible hose 51 leading to any suitable point of discharge. Extending along the top of pipe 43 from the perforate nose and secured to the pipe is an imperforate table 52 preferably formed of hard, corrosion resistant material similar to that employed for slab 21.

Post 42 being rotatable in sleeve 41, it will be clear that pipe 43 and the auxiliary spotting table 12 are free to swing in a horizontal plane. A stop shoulder 53 (Fig. 5) on arm 45 limits its rearward travel but the table can be drawn forward from its rearmost position as shown by dotted lines in Fig. 2. When it is thus drawn forward, arm 45, of course, swings with the table and by means of link 54 opens valve 55 for a purpose presently to be described.

Returning now to the steam separator, this, as previously indicated, comprises a vertically elongated tubular housing 38, the housing being closed at the bottom by a plug 56 and having a steam valve 57 screwed into the top. Steam is admitted into the separator from a supply line 58 and below the steam inlet 59 is a water overflow outlet 60 connected by line 61 to a suitable drain. A conventional trap 62 is provided in the latter line to prevent loss of steam therethrough. It will be understood that due to the extended surface of housing 38 that is exposed to ambient air, a portion of the steam admitted to the separator condenses, maintaining the separator filled with distilled water 63 to the level of the overflow outlet; above the surface of the water is steam, of course, the steam in the uppermost portion of the separator being substantially free from entrained moisture and hence referred to as "dry."

The steam supply line is connected to the separator via a heat exchanger having a housing 64 through which a steam tube 65 extends, this tube being provided with "screw thread" external fins 66 that form with the interior of the housing a spiral passageway from the air supply line 67 to the air shut-off valve 68. Air traveling through this passageway when the valve is opened, is heated by fins, which, it will be understood, are heated by the steam within tube 65. The spiral disposition of the fins provide a relatively long heated passageway in a short space and obtain maximum heat transfer to the air.

The outlet from steam valve 58 has a T fitting 69 screwed thereinto and one branch of the T is connected by a pipe 70 to the outlet from the air valve 68. The other branch of the T is connected to a hose 71 extending to a spotting gun 72; as shown, this gun has an open discharge nozzle 72a supported by a ventilated handle.

Both valves are normally closed and it will be seen from the foregoing that both have their outlets connected to the spotting gun via hose 71. Air valve 68 can be opened under control of the foot pedal 73 which, by means of a shaft extending through base member 10a, rotates a crank arm 74; this exerts a thrust on the rod 75 which in turn pivots lever 76 and opens the valve. Pedal 73 through the medium of a hollow shaft 79 turns a similar crank when the pedal is depressed and thus exerts a thrust on rod 26 to control steam valve 57.

The particular construction of the valves employed in my machine form no part of the present invention and hence they have not been detailed.

in the drawings. It is preferred, however, to employ a steam valve of the type disclosed in the co-pending application of William C. Glover, Jr., et al., Serial No. 222,024, filed April 20, 1951, to which reference may be had for a fuller understanding of their construction and operation. For purposes of the present description, it will suffice to say that upon initially depressing pedal 78, valve 51 is unseated permitting dry steam to flow from the steam space at the top of the separator through hose 10 and discharge from nozzle 12a of the spotting gun; as the pedal is depressed more, a throttle member 51a (Fig. 4) advances into a restricted throat portion 51b of the valve bore producing above and below the throttle member a pressure differential that causes water to rise in tube 82 and enter the steam stream through ports 51c. Thus, not only can the rate of steam discharge be varied by pedal 78, but also, depending upon the distance the pedal is depressed, the character of the steam can be varied progressively over a range extending from very dry to very wet. It will be noted that the lower end of the water tube 82 is provided with an enlarged cup-shaped inlet member 83, the mouth of which is covered by a screen 84 to prevent entrance of foreign matter.

Valves 55 and 68 may be identical to valve 51 except it will be understood that they function simply as shut-off valves, the tube 82 (which in the case of valve 51 accomplishes the mixing function referred to) being omitted in the case of valves 55 and 68. In other words, when pedal 73 is depressed, air under pressure from the supply line 67 is permitted to flow through the heat exchanger, thence through the valve 68 and hose 10, the heated air being discharged through the nozzle 12a of the spotting gun.

As previously explained, shut-off valve 55 is opened when the auxiliary spotting table is drawn horizontally toward the operator (see dotted lines, Fig. 2). This valve has its inlet connected to the steam space at the top of the separator and its outlet is connected through hose 86 to a Y fitting 87 mounted on the underside of pipe 43. Within the pipe is a small steam discharge tube 88 directed toward the discharge end of the pipe. The other branch of the Y fitting is connected by a hose 89 to a manually operable blow-out valve 90 set into the bottom of the separator.

Just above the latter valve is a second manually operable valve 92 which is connected by a hose 93 to a water spray gun 94. The spray gun may be of any suitable construction but preferably has a built-in shut-off valve adapted to be operated by squeezing a trigger 94a.

It will be convenient at this point to refer to the schematic diagram, Fig. 9 for a better understanding of the operation of the various parts of my machine. For purposes of description it will be assumed that valve 92 is open and the other valves all are closed which is their normal condition. Steam admitted from supply line 58 is, of course, present in the top separator 38 and distilled water 63 condensed from the steam fills the bottom portion of the separator. As indicated earlier, and as will be obvious from the diagram, opening of the pedal-controlled steam valve 51 will deliver steam to the spotting gun 12 (this being in wet or dry condition depending upon how far the valve is opened). Likewise, opening of the pedal-operated air valve 68 will deliver to the gun air which has been heated by passage through the heat exchanger 64.

Operation of the trigger on the water spray gun 94 opens the valve indicated by dotted lines whereupon cold distilled water from the bottom of the separator (which water, it will be understood is subjected to the downward pressure of the steam above its surface) is discharged in a spray from the gun.

Each of these guns may be used in conjunction with either the main spotting table, not shown in the schematic diagram, or the auxiliary spotting table. If in using the latter, the table is drawn laterally toward the operator, this opens valve 55 as previously explained, whereupon steam from the separator is discharged through hose 86 and tube 88; by injector action, the steam discharge from tube 88 draws air in through the foraminous cover 50 and causes it to travel through tube 43 in the direction of the arrows creating a strong suction at cover 50.

Sediment accumulated in the bottom of the separator may be removed periodically, as needed, by opening blow-out valve 90 and swinging the auxiliary spotting table to open valve 55. The flow of steam through the Y at the end of hose 86 now produces a suction on hose 89 which draws the sediment from the separator through hose 89 and discharges it with the steam through nozzle 88 and out the discharge end of pipe 43.

In using my machine the portion of the garment to be treated is drawn over either the main or auxiliary spotting table, depending upon the size of the garment portion involved and the type of treatment to be employed.

Certain non-water soluble stains such as ink, paint, medicine, perfume, finger nail polish, etc., require chemical treatment, the necessary chemicals and soaps being stored in bottles or other suitable containers in the tray 11; the spotted area is placed over one of the imperforate platforms 21 or 52 where the proper chemical is applied to the fabric which then may be brushed, sponged, rubbed, scraped, or otherwise manipulated to loosen the stain. The brushes, sponges, towels, chamois, etc. necessary for this purpose may conveniently be stored on tray 11 with the chemicals when they are not in use.) For flushing, feathering and drying the treated area it is moved forward over the foraminous screen at the nose of the board being used, and there is treated with one or both of the guns.

If, for example, the stain is one that would be set by heat (i. e. thermo-setting) the spray gun 94 is used to discharge cold water onto the spotted area and flush it thoroughly. Preferably this is carried out over the nose 59 of the auxiliary table which is drawn toward the operator during the process so a powerful suction draws the moisture, stain and solvent from the fabric. Use of the water spray gun reduces color bleeding from fugitive dyes to a minimum. After flushing, the vacuuming is continued while gun 72 is used to direct hot air through the fabric, which dries it almost instantly.

Moisture controlled steam from gun 72 ordinarily is used to remove water soluble spots only. For the average spot, wet steam is used for flushing the stain followed by dry steam for feathering out the spot and partially drying the fabric. Superior results and faster operation can be obtained in the case of some spots by first feathering around the edges of the spot with dry steam, then moving the nozzle of the gun spirally inward toward the center of the spot while gradually increasing the wetness of the steam and bringing the nozzle closer to the fabric; finally dry steam

is used again to remove excess moisture. The latter technique has the advantage that it tends to drive any loosened sizing toward the center of the spot where it is flushed through rather than driving it toward the rim of the spot where it tends to pile up and leave a ring. Also the spot is confined to its own area, and spreading or splattering is eliminated. Use of the vacuum nose 50 likewise is valuable in preventing spreading of stains or moisture.

Using my apparatus, steam spotting may be carried out with excellent results even on velvets, plush, suede cloth, duvetyn, corduroy and other nappy materials which heretofore could not be treated satisfactorily; badly water stained or heavily sized rayons likewise can be spotted very successfully.

As previously indicated, drying of the spotted area can be completed by means of hot air delivered through gun 72. This may be used either in conjunction with the foraminous nose section 23 of the main spotting table, or the vacuum nose section 50 of the auxiliary table. Used with the latter, drying is almost instantaneous and will absolutely prevent water rings so that the need for very careful feathering is largely eliminated and the speed of handling correspondingly increased.

An important feature of my invention resides in the provisions made for holding guns 72 and 94 where they are at all times readily available to the operator and may be put into use for the foregoing purposes with a minimum of manual movement; the guns also are arranged to return to their rest positions almost automatically in readiness for subsequent use so no lost motion on the part of the operator is involved.

In the case of water spray gun 94, the support comprises a rod 93 extending upwardly from one corner of the chemical tray, the upper end of the rod being bent over and provided with a hook to receive a depending coiled spring 97 which in turn carries the gun. When not in use, the gun thus is held out of the way of all operations carried on or in connection with the spotting tables. When needed, it may be grasped by the operator, drawn down to operating position, thus stretching the spring 97 which automatically restores it to rest position when it is released by the operator after use. The spring keeps hose 93 out of the way during use and permits free manipulation of the water spray gun.

The steam and hot air gun 72 is supported below the level of the main spotting table (and hence also out of the way), by means of a spring loop 98 whose ends extend laterally and are welded or otherwise secured to the rim 33 of basket 14. Hose 71 is threaded through the loop and is encircled, adjacent the handle of gun 72, with a hemispherical bumper or bushing 99 formed of soft rubber of similar resilient cushioning material. The bumper normally rests on the top of the loop and the weight of the hose below the loop serves to hold the gun upright so it may be grasped easily. When the gun is lifted for use, the hose obviously is drawn upwardly through the eye formed by the spring loop. After use the operator simply drops the gun in a generally vertical direction toward the loop whereupon, due to the hose being threaded through the loop and having the major portion of its weight below the loop, the gun automatically is drawn and guided back to the correct rest position. The soft resilient character of bumper 99 plus the spring construction of the loop serve to cushion the blow of stopping

the gun and thus prevent injury to the gun and the support.

From the foregoing it will be seen that my invention is one well adapted to attain all of the ends and objects hereinbefore set forth together with other advantages which are obvious and which are inherent to the apparatus.

It will be understood that certain features and subcombinations are of utility and may be employed without reference to other features and subcombinations. This is contemplated by and is within the scope of the appended claims.

Inasmuch as various modifications of the invention may be made without departing from the scope thereof, it is to be understood that all matter herein set forth or shown in the accompanying drawings is to be interpreted as illustrative and not in a limiting sense.

Having thus described my invention, I claim:

1. In a machine of the kind described, a support, a foraminous table pivotally mounted on said support to swing in a generally horizontal plane, said table having a duct whose mouth opens upwardly and is connected to the underside of said table, suction means connected to said duct, a control device normally rendering said suction means inoperative, and linkage between said table and device for actuating said device responsive to swinging of said table on said support to render said suction means operative thereby to create a downdraft through said foraminous table.

2. In a machine of the kind described, a support, a foraminous table movably mounted on said support, a duct having at one end an upwardly opening mouth whose margin is connected to the underside of the said table, a fluid injector nozzle connected into said duct and directed toward the opposite end thereof, a source of fluid under pressure, a supply line from said source to said nozzle, a valve in said line, and linkage between said table and valve for opening and closing said valve responsive to movements of said table relative to said support.

3. In a machine of the kind described, a support, a foraminous table movably mounted on said support, a duct having at one end an upwardly opening mouth whose margin is connected to the underside of said table, suction means connected to said duct, a valve controlling said suction means, and linkage between said table and valve for opening and closing said valve responsive to movements of said table relative to said support.

4. In a garment spotting machine, a support having a stationary vertical sleeve, a post rotatable and axially movable in said sleeve, a collar encircling the post above the sleeve and adjustable axially of the post, means for securing said collar to the post in any adjusted position thereon, a table fixedly mounted on the upper end of the post and effective by its weight to maintain the collar in abutting relation with the upper end of the sleeve whereby the elevation of said table is determined by the position of the collar on the post, a lever arm extending laterally from said collar and adapted when the collar is locked to the post to turn with the post upon swinging of the table in a horizontal arc about the axis of said sleeve, a valve mounted on said support, linkage between said arm and valve for operating the valve upon movement of said arm, said table comprising a foraminous generally horizontal panel having a duct whose mouth opens upwardly and is connected around its margin to the

underside of the panel, and suction means connected to said duct and controlled by said valve.

5. In a garment spotting machine, a support having a stationary vertical sleeve, a post rotatable and axially movable in said sleeve, a collar encircling the post above the sleeve and adjustable axially of the post, means for securing said collar to the post in any adjusted position thereon, a table fixedly mounted on the upper end of the post and effective by its weight to maintain the collar in abutting relation with the upper end of the sleeve whereby the elevation of said table is determined by the position of the collar on the post, a lever arm extending laterally from said collar and adapted when the collar is locked to the post to turn with the post upon swinging of the table in a horizontal arc about the axis of said sleeve, a fluid conduit containing a flow-controlling valve mounted in fixed relation to said support, and linkage between said arm and valve for operating the valve upon movement of said arm.

6. In a spotting machine, a stationary support, a foraminous table movably mounted on said support to swing in a generally horizontal plane, a duct having at one end an upwardly opening mouth whose margin is connected to the underside of the table, a nozzle connected into said duct and directed toward the opposite end thereof, a closed vessel, a source of steam under pressure connected into said vessel, said vessel having an extended exterior heat radiating surface to cause condensation of steam entering the vessel from said source, a condensate outlet line communicating with said vessel at the bottom thereof, a steam injector connected to the other end of said line for imposing suction thereon, a steam supply line extending from said steam source to said injector, a valve in said last line, mechanism connected to said table for opening and closing said valve responsive to swinging of said table on the support thereby to cause said injector to impose suction on said condensate line intermittently, and a steam discharge line leading from said injector to said nozzle whereby the steam from said injector is discharged through said nozzle toward said other end of the duct.

7. In a spotting machine as in claim 6 a manually operable shut-off valve in said condensate outlet line between said vessel and said injector.

8. In a spotting machine, a closed vessel, a source of steam under pressure connected into said vessel, said vessel having an extended exterior heat radiating surface to cause condensation of steam entering the vessel from said source, a condensate outlet line communicating with said vessel at the bottom thereof, a steam injector connected to the other end of said line for imposing suction thereon, a steam supply line from said steam source to said injector, a valve in said last line, a stationary support, a pan movably mounted on said support, linkage between said pan and said valve for opening and closing the valve responsive to movement of the pan relative to said support thereby to cause said injector to impose suction on said condensate line intermittently, a foraminous cover over said pan, said pan having an outlet opening below its upper rim, and a second injector associated with said outlet opening and connected to the discharge of said first injector for creating a down draft through said foraminous cover into said pan when said valve is open.

9. In a spotting machine, a closed vessel, a source of steam under pressure connected into

said vessel, said vessel having an extended exterior heat radiating surface to cause condensation of steam entering the vessel from said source, means limiting the maximum level that said condensate can attain in the vessel thereby to provide a steam space in the vessel above the surface of the condensate, a condensate outlet line communicating with said vessel at the bottom thereof, a steam injector connected to the other end of said line for imposing suction thereon, a steam supply line from said steam source to said injector, a valve in said last line, a stationary support, a table pivotally mounted on said support to swing in a generally horizontal plane, linkage between said table and said valve for opening and closing the valve responsive to swinging of the table thereby to cause said injector to impose suction on said condensate line intermittently, a steam outlet line extending from said steam space in the vessel and having a discharge nozzle at the end thereof, and a valve in said last line to control the flow of steam therethrough, at least part of said last line being flexible to permit movement of said nozzle relative to said table.

10. A spotting machine as in claim 9, wherein said vessel is vertically elongated, a stationary base secured to the lower end of said vessel and supporting same in upright position, said support for said pivotal table being secured to the upper portion of said vessel whereby said table is carried by said vessel.

11. In a spotting machine, a stationary base, a vertically elongated closed vessel extending upwardly from said base and forming a post, a table pivotally mounted on said post above the base to swing in a generally horizontal plane, a source of steam under pressure connected into the vessel, said vessel having an extended exterior heat radiating surface to cause condensation of steam entering the vessel from said source, means limiting the maximum level that the condensate can attain in the vessel thereby to provide a steam space in the vessel above the surface of the condensate, a steam outlet line from the steam space in the vessel having a nozzle at the end thereof, means including a mixing valve associated with said line for controlling the steam flow therethrough to the nozzle and for optionally introducing condensate into said steam flow to temper the steam, at least part of said line being flexible to permit movement of said nozzle relative to the table, said table comprising a foraminous generally horizontal panel with a duct having at one end an upwardly opening mouth whose margin is connected to the underside of said panel, an injector nozzle connected into said duct and directed toward the opposite end thereof, a line from said steam source to said injector nozzle, a valve in said last line, and linkage between said table and said last valve for opening and closing said last valve responsive to swinging of said table on said post.

12. In a spotting machine, a stationary base, a vertically elongated closed vessel extending upwardly from the base and forming a post, a table pivotally mounted on said post above the base to swing in a generally horizontal plane, a source of steam under pressure connected into the vessel, said vessel having an extended exterior heat radiating surface to cause condensation of steam entering the vessel from said source, means limiting the maximum level that the condensate can attain in the vessel thereby to provide a steam space in the vessel above the surface of the con-

densate, a steam outlet line extending from the steam space in the vessel and having a steam discharge nozzle at the end thereof, a condensate outlet line extending from the lower portion of the vessel and having a condensate discharge nozzle at the end thereof, valves in the respective lines to control the flow therethrough to said nozzles, said lines being flexible to permit movement of the nozzles relative to said table, said table comprising a foraminous generally horizontal panel with a duct having at one end thereof an upwardly opening mouth whose margin is connected to the underside of said panel, an injector nozzle connected into said duct and directed toward the opposite end thereof, a line from said steam source to said injector nozzle, a valve in said last line, and linkage between said table and said last valve for opening and closing said last valve responsive to swinging of said table on said post.
